THE D. T. OWEN COMPANY, OF CLEVELAND, OHIO, A CORPORATION.

COMBINED BED AND SOFA.

1,150,299.

Specification of Letters Patent. Patented Aug. 17, 1915.

Application filed March 21, 1912. Serial No. 685,173.

To all whom it may concern:

Be it known that we, DAVID T. OWEN and EDWARD N. BROWN, citizens of the United States, residing at East Cleveland, in the county of Cuyahoga and State of Ohio, have invented certain new and useful Improvements in a Combined Bed and Sofa, of which the following is a specification.

Our invention consists in certain improvements in a combined bed and sofa of the folding type, all substantially as shown and described and particularly pointed out in the claims.

In the accompanying drawings, Figure 1 is a cross section of the structure folded and showing the inside of one end of the supporting frame. Fig. 2 is a front elevation of one end with a portion of the upholstering broken away and disclosing one of the end links for supporting the seat when the seat is folded and for suspending the same when open as in Fig. 7. Fig. 3 is a longitudinal sectional elevation on line 3—3, Fig. 1, and Fig. 4 is a sectional elevation on line 4—4, Fig. 1. Fig. 5 is a rear elevation showing the parts folded, and Fig. 6 is a perspective view of the angle iron back rail of the frame which connects the ends or end section, as seen also in Figs. 1 and 7. Fig. 7 is a similar view to Fig. 1, but showing the bed unfolded. Fig. 8 is an inside view of one of the ends or end sections or members of the complete frame showing the parts directly attached thereto. Fig. 9 is a perspective view from the inside of an end section of the detachable front board of the complete frame and a section of the seat and the truss and other parts therewith as hereinafter fully described. Fig. 10 is a plan view of the spring bed bottom open or unfolded.

In the structure as thus shown the main frame comprises the two end members or sections 2 and the front and rear connecting bars or rails 3, 4 and 5, which are detachably but rigidly affixed to the said end members and together constitute a rigid frame-work in and upon which all the other parts are mounted. Inclined braces 6 rigidly connect

the rear rails 3 and 4 and the truss bars 5 at 50 the front likewise are rigidly connected and separably unite the ends 2 at the front, so that the whole constitutes a knock-down structure easily separated and assembled.

The bed proper comprises a spring bottom 9 in two parts corresponding to the front and rear sections thereof, and which is practically continuous and stretched upon the frames 7 and 8, as seen in Fig. 10, and which frames together constitute practically 60 a complete border around the said spring bottom. The said truss-bars are supported on the main frame through standards 11 affixed to the ends of said truss-bars, detachable engagement being made by hooks 65 h on the end frames 2 through slots 10 in the bottom portion of the standards. The upper ends of said standards are confined in keepers 12 from lateral movement, and a finishing board 13 is fixed to the outside of 70 the truss and serves as a support for the seat 8 and the apron 15 therefor. Heavy wire links 7 serve as suitable supports between the front of the seat and the board 13, suitable small brackets d and d' being provided 75 for said link connections. Pivot and operating arms a and a' are provided on each bed section at its ends and inner angles which are pivotally united at 18 and are supported together from the main or primary pivot 19 through hole 20 in the top of 80 the said standard 11 and through an ear or boss at the base of arm a' on the front bed section. The said front section is thus supported on these primary fixed pivots 19 at 85 its ends, and through the arms a and a' the rear section is mechanically raised and lowered within limits by the operation of the front section as seen in Figs. 1 and 7 respectively. At its rear the said rear section 90 is free to swing up and down within the limits of the chains c , Figs. 1 and 7, and the front is supported by the arms a as above described. However, when the rear frame or section of the bed bottom is raised by 95 swinging the front section to open position it rides up onto carriers or supports 21 at each end of the main frame by means of

pins or projections 22 fixed in the said bed frame adapted to rest upon the top of said carrier in supporting position, as seen in Figs. 7 and 10.

5 Now, having the foregoing parts constructed and arranged substantially as above described, the matter of folding and unfolding the bed becomes important and involves possibly the most important features in this 10 application. For example, it is material that the bed should be opened with the exercise of the least possible manual effort so as to avoid excessive strain or burden in making the change, and it is also material 15 that the front or seat section of the bed should be arranged for release without special exertion and especially without bodily lifting the back to enable this to be done. The present construction therefore is such 20 that the back will hold the seat down when it is closed and release it when the seat is to be raised and inverted and all without undue effort or exertion by the user. To these ends the said bed sections are provided with 25 springs 25 in the angle of their pivot between arms a and a' and which are so placed that they will exert a raising or lifting tension or effect upon the seat up to nearly a half way open position and with the greatest 30 tension of said springs in the lowest position of the seat, as in Fig. 1, where the seat is locked down to be occupied. It follows with such a construction and arrangement of the parts that the springs themselves 35 will practically open the seat when it is released by pushing the bottom of the back b rearward and leave very little to be done by hand except to turn the seat forward and to rest on the legs 26. The peculiar 40 arrangements of the springs with respect to the said sections and particularly to the front section works this result, and to this end each spring is connected with the bottom of rear frame 8 back from its immediate front by a link 27 as seen in Fig. 45 7, and at the other end by means of a link 28 with the top edge of the outer section. It follows when the front or outer section is being folded and has passed the half-way 50 position that the said springs are stretched as seen in Fig. 1 and thus begin to exert a tension which increases with the closing down of the said front section. The reverse effect is present when the said section 55 is released by pressing the back b rearward and thus releasing said section to the lifting action of the said springs. The back b is suspended from the rail or bar 4 and adapted to be mechanically swung forward over 60 the rear of the said front or seat section of the bed, as seen in Fig. 1, by means of curved arms 30 pivoted on the main frame at about their middle and having their concave sides uppermost. Each arm is provided with a

lateral or inwardly extending lip 31, Fig. 65 3, at its inner end adapted to engage beneath the seat frame in supporting relation while the other end of the said arm in this instance is shown as connected by a link 33 with an open slot in a bracket 34 fixed on the bottom rail of the back b . Link 33 is shown as a two-part screw member, permitting adjustment in fitting and fixing the operative relations between the back and the seat. It follows with this construction that 70 when the said front bed or seat frame is depressed in its last closing position it strikes the lip 31 and causes the other end of said lever to be thrown inward and press the back b inward also over the rear edge of the said seat or bed frame. The stops 35 prevent the said arms from dropping below a given point and serve as rests therefor. When the back b is released it will swing into hanging position by its own gravity as seen 80 in Fig. 7 and in which position the front end of the arm 30 is raised. Then as the front bed section is folded and depressed to closed position it will strike the lip 31 on the said lever and automatically press the 90 back b forward over the edge of said section and thus both hold the seat section down where it belongs and also effectually brace the back b when the seat is occupied. Obviously the greater the weight upon the seat 95 the more effectually will the back be locked in both engaging and supporting positions. When the seat is unoccupied and it is to be raised or opened it is only necessary to press the bottom inward by hand and thus liberate 100 the seat frame. The springs 25 will then instantly assert themselves and raise the seat to more or less open position.

Respecting the seat s as such it will be seen in Fig. 7 that it is mechanically free 105 from the special spring bottom provided therefor and that it is supported at the front by the links 7 and at the rear by means of metallic or equivalent straps 38 directly to the bed frame 7. The said seat bottom 110 proper comprises two rectangular frames 40 or fairly rigid wire and an open wire mesh 41 stretched on each frame, and a series of helical springs 42 disposed at suitable intervals between said wire mesh, the whole 115 constituting a practically separate wire spring mattress for the seat. The frame 40 may be suitably wired or attached to the bed spring beneath, but is preferably free of direct attachment therewith to permit the bed bottom 9 to have independent play, except as hereinafter noted.

It has been observed that the respective spring strands 9 which constitute the bed bottom proper are stretched within the respective sections 7 and 8, but it is also necessary that there should be continuity in the bed bottom which is obtained by uniting the 125

said spring strands by clips 9' over the entire area of the bed bottom, but leaving a detached space of about fifteen inches at each end on the fold line of the respective sections, see Figs. 1, 4 and 10. This accommodates the unavoidable separating of said spring bottom especially when the sections are folded into the spaced relations shown in Fig. 1. In this operation, the middle connected portion of the bed bottom 9 is drawn inward away from the apron 15, but seat *s* is nevertheless spring supported by the spring frame 40 which rests in part upon the bed bottom 9 and extends in part over the gap at the front of the bend 43 of the bed bottom, see Fig. 1. The continuity of the bed bottom is necessary to make it as one bottom for occupancy and this effect is further enhanced by having the seat spring frame 40 extend to or beyond the split or unconnected portion of the bed bottom 9 on the fold line thereof as seen in Fig. 10.

The chains *c* are serviceable not only as supports for the rear bed section when it is down, as in Fig. 1, but they serve also to keep the mattress and bedding (not shown) upon the bed sections during folding and unfolding operations and when folded.

By operatively combining the back and the seat as herein I avoid any gap or open space between said parts and use the weight of the person occupying the sofa to make closure between said parts effective. The means for accomplishing this result may be other than that shown, but to be effective, an accommodating play of the back to the seat must be considered, otherwise interference in operations and imperfect locking and closure between the parts will result.

Locking engagement between the frame section 7 with the back *b* is localized at two places, by a rounded rib *r* on the pivot bracket *p* for each leg 26. Two such ribs or projections *r* are shown in Fig. 5, and these ribs form part of the pivot-bracket for each leg 26, as described.

The seat bottom proper or spring mattress 40 for the seat has been described as operatively independent of the bed springs and so it is except at one end where a couple of spring wire coils 44 at each end (Fig. 10) connect one of the border wires of the said frames 40 with the bed frame and afford something of an auxiliary support for the middle of the bed and where there would otherwise be tendency to sag and for the front edge of the seat when the bed is folded, as occurs in Fig. 1, and where the said construction serves to supplement the links *l*. The said links *l* also sustain the seat *s* when unfolded, Fig. 7, and thus relieve the upholstering apron 15 of all weight and strain. It will be noticed that the said seat is not attached to its spring bottom and hangs loose when the bed is occupied, but

when the bed is folded the seat, which is in the form of a pad, is stretched tightly and closely over its spring bottom as seen in Fig. 1. When occupied as a davenport couch, the load is distributed and carried by both the seat spring frame 40 and the spring bottom 10.

Chains *c* have hooks *c'* to detachably connect with rear rails 3, and the entire bed is of a knock-down character to facilitate handling and shipment.

1. In combined folding beds and sofas, a folding bed bottom having a bed spring and a separate spring bottom for a seat resting thereon and having supporting coils at its ends connected with the frame of said bottom.

2. A combined sofa and bed having a folding section with a frame and a spring stretched therein, in combination with a spring bottom for the sofa seat comprising an approximately rigid rectangular frame and springs therein separate from said folding section and resting thereon, and connections between the inner portion of said spring bottom and said frame.

3. A combined bed and sofa comprising a main frame, a folding front bed section, a separate seat supporting spring bottom mounted on said bed section, an upholstered seat and links supporting the front thereof on the said main frame.

4. A combined bed and sofa comprising a folding bed frame and a separate seat supporting spring bottom mounted thereon and connected with said bed frame at its inner portion and ends, in combination with a seat supported on the said bed frame at its rear edge and links supporting the front edge of said seat, said links being in sustaining relation immediately outside of said spring bottom and coöperating therewith.

5. In a combined bed and sofa, a main frame and a folding frame therein, a seat supporting spring bottom mounted on said folding frame and a seat thereon, links supporting the said seat at its front from said main frame and arms pivoted on said main frame and supporting the rear of said folding frame and the said seat.

6. In a combined bed and sofa, a main frame and a folding front bed section, a spring bottom for a seat mounted on said bed section, a seat adapted to rest on said spring bottom and links supporting the front portion thereof and an apron for said seat engaged at its lower edge with said main frame and concealing said links.

7. In a combined bed and sofa, a pair of bed sections having arms at their meeting edges pivotally connected, a spring seat bottom supported on the front bed section and a seat thereon, links supporting the said seat independently of said spring seat bottom at the front of said arms and means

fastening the said seat to the rear of said bed section.

8. A combined folding bed and sofa having a main frame with end sections and a truss at front of said frame having standards at its ends provided with holes in their top, in combination with folding bed sections having fixed pivots in said holes and the said sections having arms with a pivot point between them adapted to swing in a

radius about said fixed pivots as said bed sections are opened and folded.

In testimony whereof we affix our signatures in presence of two witnesses.

DAVID T. OWEN.
EDWARD N. BROWN.
